UNITED STATES PATENT OFFICE.

WILLIAM S. LEE, OF CHARLOTTE, NORTH CAROLINA, ASSIGNOR TO REALTY INVESTMENT AND SECURITIES COMPANY OF CHARLOTTE, OF CHARLOTTE, NORTH CAROLINA, A CORPORATION OF NORTH CAROLINA.

RACK FRAME.

Application filed July 8, 1924. Serial No. 724,919.

This invention is an improvement in racks, and with respect to its more specific features to the character of racks employed to fend drift and the like from water wheels 5 and like engines.

In the usual construction of rack of the character in question, the rack is either an integral structure or composed of a number of integral sections having an aggregate area 10 equal to that of the rack desired.

The breakage of a rack bar necessitates the removal of the entire structure when of an integral character, or of an entire section when of the sectional type, so that the 15 ultimate loss from the breaking of the bar includes the cost of the new section or rack, and the expense of removing the old and placing the new.

When sectional, the area of the rack must 20 be calculated with the area of a single section as a unit; that is the sections must be of a size such that a specified number arranged in a specified relation will be of the required aggregate area. Hence a rack constructed in the usual manner must be designed for the particular place where it is to be set, and there is no flexibility such as would permit the rack to be fitted on the 25 spot to the requirements of the particular situation.

Racks of this character are difficult to clean properly. The teeth of the rake, by means of which the drift is removed, catch upon the cross portions of the rack when the 30 teeth are drawn between the bars, and such portions of the rack cannot be cleaned properly, resulting in an increasing accumulation of drift.

An object of the present invention is to 35 provide a rack of simple and inexpensive construction, and of a character so flexible that it may be built to fit practically any situation.

Another object is to provide a rack where- 40 in each bar is independent of the remaining structure and readily removable therefrom when desired for any purpose.

Another object is to provide a construction 45 of support for the bars, such that the teeth of the cleaning rake will not catch therein, but will slip readily past, thereby to facilitate the keeping of the rack clean.

To the accomplishment of the foregoing 50 and such other objects as may hereinafter appear, my invention consists in the ele-

ments and their relation one to the other, as hereinafter defined in the appended claims, reference being had to the accompanying drawings forming a part hereof, which show a preferred embodiment of apparatus for carrying out the method, and in 60 which:

Fig. 1 is a front view of the improved rack.

Figs. 2, 3, 6, 7, 8 and 9, are sections on the 65 lines 2—2; 3—3; 6—6; 7—7; 8—8 and 9—9, respectively, of Fig. 1.

Fig. 4 is a front view of the upper portion 70 of the rack, with parts broken away.

Fig. 5 is a rear view of the upper portion, 75 with parts broken away.

Fig. 10 is a front view of the lower portion of the rack, with parts broken away.

Fig. 11 is a rear view of the same.

In the present embodiment of the invention, the improved rack is composed essentially of a series of independent bars, and means to hold the bars in spaced relation, with the adjacent edges of the bars at each face of the rack in the same plane. The bars 80 are suitably spaced laterally, and the rack may be a continuous structure from side to side, or it may be composed of independent sections, as in the present instance, wherein each section is arranged in an independent 85 opening 1 in a wall 2 of a pen stock or the like, the openings being arranged alongside each other as shown.

Each section is composed of a series of bars 3, which may be of a length to extend 90 from top to bottom of the rack section, and of a suitable width and thickness. The bars at the inlet face of the rack are supported at their tops and bottoms only, while at the outlet face of the rack, that is the rear face, 95 the bars are supported intermediate their ends. The supporting means includes a number of members, each in the form of an angle plate, composed of two portions extending at an angle with respect to each other, one of the portions notched at spaced intervals to receive the bars, and the other

serving as an attaching means for the member. The holding member at the top is an angle plate 4, consisting of portions extending at an obtuse angle, and one of the portions is riveted or otherwise secured to an angle plate 5, supported in a manner to be presently described, while the other portion which extends downwardly and rearwardly, 100 105 110

is notched at regular intervals, as shown at 6 in Fig. 4 to receive the bars 3. The holding member at the bottom of the bars is an angle plate 7, the portions of which extend 5 at a right angle, and one of these portions is riveted to a plate 8 supported in a manner to be presently described, the other portion being notched as indicated at 9 to receive the bars.

- 10 Intermediate their ends the bars are held in spaced parallel relation on the outlet or rear face of the rack by angle plates 10 and 11, any number of which may be provided, in accordance with the length of the bars, 15 and the height of the rack. The angle plates 10 and 11 are similar to the angle plates 7 before mentioned, each having one portion notched at 12 to receive the bars, and another portion extending at substantially right angles thereto, serving as a means to support the plate.

Each of the angle plates 11 is supported by an I beam 13, the ends of which are anchored in the walls of the opening 1 in 25 which the rack section is arranged. The angle plates 11 are riveted or otherwise secured to the lowermost of the forward flanges of the I beam, as shown in Fig. 3, and the I beams 13 are so spaced that sufficient rigidity will be imparted to the bars 3.

The bars preferably extend the full length of the rack for convenience in cleaning, and at their lower ends they rest upon a plate 14 whose ends are anchored in the walls of 30 the openings 1. This plate 14 is of a width corresponding to the aggregate width of the I beam 13 previously mentioned, and a bar 3, as clearly shown in Fig. 3, and an angle plate 15, is riveted or otherwise secured to the plate 14, forming an abutment for the rear edges of the bars 3. The attached portion of the angle plate 7 at the front serves a like purpose for the front edges of the bars, and the plate 8 before mentioned, 35 is connected to the plate 14 by means of an angle plate 16 beneath the plate 14. A channel beam 17 is provided at the top of the rack, the ends thereof being anchored in the walls of the opening 1, and a plate 18 is 40 riveted or otherwise secured to the front edge of the channel beam. This plate extends forwardly as shown, and is notched to receive the bars 3. The angle plate 5 before mentioned, rests upon the top of the bars 3, 45 as shown in Fig. 3, and is secured to the plate 18 by means of bolts and nuts 19. When it is desired to remove a bar 3 for any purpose, the elements 4 and 5 are detached from the plate 18 by releasing the 50 bolts and nuts 19. This permits the selected bar to be lifted vertically to disengage the lower end from the abutments constituted by the angle plates 7 and 15.

The rear holding members for the bars 55 3 are of the type shown at 11, except the top-

most which is of the type indicated at 10, and all of the intermediate holding members are in the rear of the rack, so that the entire length of the bars at the front or inlet side of the rack is free and unobstructed, offering no impediment to the teeth of the cleaning rake. The horizontal portion of the angle plate 7 limits the downward movement of the rake and defines a starting point for the upward movement. 70 When the teeth reach the upper end of the rack, they engage the inclined portion of the angle plate, and are deflected outwardly, so that the rack presents nothing in the nature of an obstruction for the teeth to catch upon. 75

The channel plate 17, the I beams 13, and the plate 14 of each section, are connected at their ends by means of angle plates 21 to vertically arranged beams 20-20^a, and these beams are anchored within the material of the penstock wall at opposite sides of the opening 1, in which the rack section is arranged, as clearly shown in Fig. 2. Suitable anchors 22 are connected with the beams 20, with the channel beams 17, and with the plate 14, for engaging deep within the material of the pen stock wall, thereby to firmly anchor the frame of the rack section, constituted by the beams 17, 13, 20-20^a, and the plate 14. It will be noticed, referring to Fig. 2, that there are four sections of the rack in the instance shown, and four openings are provided for the sections. The central openings 1 are spaced apart by a wall 23, which is of greater thickness than the walls 24, which space apart the two racks at each side of the center. The beams 20^a, which are embedded in the walls 24, are in effect I beams, but each is composed of two channel beams arranged back to back in spaced relation, and secured together by means of plates 25, which are riveted or otherwise secured to the flanges of the beams. All of the sections are alike, and each is a complete rack within itself. It 90 will be obvious that the entire width of the rack may be a single section if desired.

In building the rack sections, the frames may be anchored in the pen stock wall encircling the openings 1, and the bars placed whenever desired. In cleaning the rack, the rake teeth move between the bars, but do not extend far enough to engage the supporting members at the rear of the bars, and the rake has free movement from the top to the bottom of the rack. Should a bar become broken or otherwise damaged, it is easily removed and replaced by a new bar, if necessary, merely by loosening the nuts of the bolts 19, and removing the elements 4 and 5, which releases the bars.

What is claimed as new is:

1. A rack of the class described, comprising a plurality of independent bars, a plurality of independent means to hold the bars 100

- in a common plane, and in spaced substantially parallel relation, the holding means including means to prevent longitudinal sliding movement of the bars in one direction, and a detachable element preventing longitudinal movement of the bars in the opposite direction, and permitting when detached independent movement of any selected bar.
- 10 2. A rack of the class described, comprising a plurality of independent bars, a plurality of independent means to hold the bars in a common plane, and in spaced substantially parallel relation, the holding means including means to prevent longitudinal sliding movement of the bars in one direction, and a detachable element preventing longitudinal movement of the bars in the opposite direction, and permitting when detached independent movement of any selected bar, the holding means also including members extending transversely of the bars at opposite sides thereof, and notched to receive the bars.
- 15 3. A rack of the class described, comprising a plurality of independent bars, means to hold the bars in spaced parallel relation and in a common plane, said means comprising members at the top and bottom of the rack, notched to receive the bars, and another member at the opposite side of the bars intermediate the ends thereof and similarly notched.
- 20 4. A rack of the class described, comprising a plurality of independent bars, means to hold the bars in spaced parallel relation and in a common plane, said means including a support for the lower ends of the bars, and members at opposite sides of the bars notched to receive the bars, the members at one face of the rack being staggered with respect to those at the other face.
- 25 5. A rack of the class described, comprising a plurality of independent bars, and means to hold the bars in spaced parallel relation and in a common plane, said means including members at the opposite faces of the rack notched to receive the edges of the bars, said members above the bottom of the rack inclined upwardly to deflect the teeth of a cleaning rake.
- 30 6. A rack of the class described, comprising a plurality of independent bars, and means to hold the bars in spaced parallel relation and in a common plane, said means including members at opposite faces of the rack notched to receive the edges of the bars, said members inclining toward the ends of the rack.
- 35 7. A rack of the class described, comprising a plurality of independent bars, and means to hold the bars in spaced parallel relation, including members notched to receive the bars, said members intermediate the ends of the bars at one face of the rack,
- 40 and at the top and bottom of the bars at the other face, thereby to leave the bars unobstructed between the top and bottom at the last named face.
- 45 8. A rack of the class described, comprising a plurality of independent bars, and means to hold the bars in spaced parallel relation, including members notched to receive the bars, said members intermediate the ends of the bars at one face of the rack, and at the top and bottom of the bars at the other face, thereby to leave the bars unobstructed between the top and bottom at the first named face, the member at the top of the bars inclining downwardly and toward the other face of the rack.
- 50 9. A rack of the class described, comprising a plurality of independent bars, means engaging the ends of the bars to hold them in spaced relation against lateral movement, and the holding means including means to hold the bars from longitudinal movement in one direction and a detachable element for normally restraining them from longitudinal movement in the opposite direction.
- 55 10. In a rack of the class described, including a plurality of independent bars, means engaging the opposite ends of the bars to prevent lateral movement thereof, and including means engaging the bars at one face of the rack to hold them in spaced relation, one of said means detachable to permit removal of a bar or bars.
- 60 11. A rack of the class described, comprising a plurality of independent bars, a frame having means to support the bars against longitudinal movement and movement lateral with respect to the frame, one of said means detachable to permit removal of a bar or bars, and each of said means having mechanism to hold the bars in spaced relation.
- 65 12. A rack of the class described, comprising a plurality of independent bars, a frame having means to support the bars against longitudinal movement and movement lateral with respect to the frame, one of said means detachable to permit removal of a bar or bars, and each of said means having mechanism to hold the bars in spaced relation, said mechanism engaging the bars at one face of the rack.
- 70 13. A rack of the class described, comprising a plurality of independent bars, a frame having means to support the bars against longitudinal movement and movement lateral with respect to the frame, one of said means detachable to permit removal of a bar or bars, and each of said means having mechanism to hold the bars in spaced relation, said mechanism engaging the bars at one face of the rack, and other holding mechanism at the other face of the rack intermediate the ends thereof.
- 75 14. A rack of the class described, comprising

- ing a plurality of similar sections, each including a plurality of individual bars, and a frame having means to support the bars against longitudinal movement and against movement lateral with respect to the frame, one of said means detachable to permit removal of a bar or bars, and each of said means having mechanism to hold the bars in spaced relation.
- 10 15. A rack of the class described, comprising a plurality of similar sections, each including a plurality of individual bars, and

a frame having means to support the bars against longitudinal movement and against movement lateral with respect to the frame, one of said means detachable to permit removal of a bar or bars, and each of said means having mechanism to hold the bars in spaced relation, said mechanism engaging the bars at one face of the rack.

Signed at Charlotte, in the county of Mecklenburg and State of North Carolina, this 23 day of June A. D. 1924.

WILLIAM S. LEE.
